United States Patent Office

Des. 181,546
Patented Nov. 26, 1957

181,546

BOX FOR A WATCH BAND OR THE LIKE

Worthen Paxton, Rye, N. Y., assignor to Braun-Crystal
Mfg. Co., Inc., Middle Village, N. Y., a corporation of New York

Application November 29, 1955, Serial No. 39,079

Term of patent 3½ years

(Cl. D80—5)

FIG. 1.

FIG. 2.

FIG. 3.

FIG. 4.

FIG. 5.

Fig. 1 is a top plan view of a box for a watch band or the like, showing my new design.

Fig. 2 is a front elevational view.

Fig. 3 is a rear elevational view.

Fig. 4 is a bottom plan view.

Fig. 5 is an end elevational view.

I claim:

The ornamental design for a box for a watch band or the like, substantially as shown.
